UNITED STATES PATENT OFFICE.

SHIRLEY S. LLOYD, OF NEW YORK, N. Y.

DESIGN FOR WALL-PAPER.

55,951.

Specification for Design.

Patented Aug. 3, 1920.

Application filed October 30, 1919. Serial No. 334,543. Term of patent 7 years.

To all whom it may concern:

Be it known that I, SHIRLEY S. LLOYD, a citizen of the United States, residing at New York, in the county and State of New York, have invented a new, original, and ornamental Design for Wall-Paper, of which the following is a specification, reference being had to the accompanying drawing and specimen, forming part thereof.

The drawing is a plan view of a piece of wall paper showing one repeat of the pattern constituting my design.

I claim:

The ornamental design for wall paper, as shown.

SHIRLEY S. LLOYD.
